DESIGN FOR A COMBINATION TUMBLER
HOLDER AND ASH TRAY

Carmen M. Stacey, Toledo, Ohio

Application June 7, 1933. Serial No. 48,308

Term of patent 3½ years

To all whom it may concern:

Be it known that I, CARMEN M. STACEY, a citizen of the United States of America, residing at Toledo, Lucas County, Ohio, have invented a new, original, and ornamental Design for a Combination Tumbler Holder and Ash Tray, of which the following is a specification, reference being had to the accompanying drawing, forming part thereof.

Fig. 1 is a plan view of a combination tumbler

holder and ash tray embodying my new design;

Fig. 2 is a front elevation of the device of Fig.

1; and

Fig. 3 is a view of the device from the right of

Fig. 2.

I claim:

The ornamental design for a combination tumbler holder and ash tray as shown.
